UNITED STATES PATENT OFFICE.

GEORGE A. WEBER, OF NEW YORK, N. Y., ASSIGNOR TO WEBER RAILWAY JOINT MANUFACTURING COMPANY, OF NEW YORK, N. Y., A CORPORATION OF WEST VIRGINIA.

RAIL-CHAIR.

SPECIFICATION forming part of Letters Patent No. 760,501, dated May 24, 1904.

Application filed February 2, 1904. Serial No. 191,653. (No model.)

To all whom it may concern:

Be it known that I, GEORGE A. WEBER, a citizen of the United States, and a resident of the borough of Manhattan, city, county, and State 5 of New York, have invented certain new and useful Improvements in Rail-Chairs, of which the following is a specification accompanied by drawings.

This invention relates to railroad-rail joints, 10 but more particularly to the supporting-chairs or shoe-angles for such joints; and the object of the invention is to improve upon the construction of such rail-chairs or shoe-angles and increase their strength and efficiency. 15 Further objects of the invention will hereinafter appear; and to these ends the invention consists of a rail-chair embodying the features of construction, combinations of elements, and arrangement of parts, substantially 20 as hereinafter fully described and claimed in this specification and shown in the accompanying drawings, in which—

Figure 1 is a transverse sectional view of a rail-joint provided with a rail-chair embodying the invention. Fig. 2 is a side elevation 25 of the joint, showing the construction of the chair.

Referring to the drawings, A and B represent the meeting ends of rails supported upon 30 a rail-chair C, having a base-plate D and upright E extending therefrom.

To illustrate the invention, in this instance a suitable form of joint is shown in combination with the chair. The joint in this instance is shown insulated, although any kind of a joint may be used with the chair. At each side of the webs of the rails are provided the insulating filling-blocks F, which may be of wood, and the bolts G are suitably insulated 35 by means of the insulating-sleeves H and washers I. The base of at least one of the rails is supported upon the insulation J. In this instance improved means are shown for maintaining the insulation J beneath the rails, a holding device K being used in the form of a wire, of metal or other suitable material, which is interwoven with or suitably connected to 40 the insulation J and extended up between one

of the filling-blocks F and the chair, so that when the parts are clamped together the holding device K maintains the insulation J in position. The holding device, if of metal, should be provided at one side of the joint only, to prevent completion of the circuit between the rails. At the side of the joint opposite the 55 upright is arranged a strap L, extending continuously across the joint, suitably insulated by sleeves H and washers I.

The improved chair C is provided with a strengthening-web O to increase the vertical 60 depth or height of the chair at the portion thereof at which strength is most needed—namely, the central portion. As shown and in accordance with this invention, the edge of the base-plate D opposite the upright E is centrally bent out of the plane of the base to form the web O. In this instance the web O is bent in the opposite direction from the upright E. In combination with the strengthening-web O the strengthening rib or fillet P 70 is provided, forming a spiking rib or flange at the juncture between the base and the upright.

The chair made in accordance with this invention is strong at the juncture of the base 75 and upright and is also of increased strength over other chairs at the central portion, where the greatest strain comes.

Obviously some features of this invention may be used without others, and the invention 80 may be embodied in widely-varying forms.

Therefore, without limiting the invention to the constructions shown and described nor enumerating equivalents, I claim, and desire to secure by Letters Patent, the following:

1. A rail-chair or shoe-angle, comprising a base-plate and an upright extending substantially at right angles from the junction therewith, the edge of said base-plate opposite the upright being centrally bent out of the plane 90 of the base, to form a strengthening-web, for substantially the purposes set forth.

2. A rail-chair or shoe-angle, comprising a base-plate and an upright extending substantially at right angles from the junction therewith, the edge of said base-plate opposite the 95

upright being centrally bent in the opposite direction to the upright, to form a strengthening-web, for substantially the purposes set forth.

- 5 3. A rail-chair or shoe-angle, comprising a base-plate and an upright extending therefrom, with a strengthening-rib or spiking-flange at the outside of the juncture between the base and upright, the edge of said base-plate opposite the upright being centrally bent

in the opposite direction to the upright, to form a strengthening-web, for substantially the purposes set forth.

In testimony whereof I have signed this specification in the presence of two subscribers.

GEORGE A. WEBER.
